Attys.

UNITED STATES PATENT OFFICE.

AUBREY D. McCROSKEY, OF LOS ANGELES, CALIFORNIA.

DOLL.

1,280,055.

Specification of Letters Patent. Patented Sept. 24, 1918.

Application filed April 22, 1918. Serial No. 230,009.

To all whom it may concern:

Be it known that I, AUBREY D. McCROSKEY, a citizen of the United States, residing at Los Angeles, in the county of Los Angeles, 5 and State of California, have invented new and useful Improvements in Dolls, of which the following is a specification.

My object is to make a doll head having mechanically operated eyes, and my invention 10 consists of the novel features herein shown, described and claimed.

Figure 1 is a side elevation of the head, parts being broken away and shown in section to show the construction and operation 15 of the mechanism.

Fig. 2 is a sectional detail on the line 2-2 of Fig. 1.

A head 1 is made hollow. An enlargement 2 is formed in the top of the head 20 1 to extend into the hollow 3. A post 4 is screwed into this enlargement 2, said post being centrally located in a vertical position.

A shaft 5 is fixed across the hollow 3 with 25 its ends embedded in the material of the wall; the shaft 5 being in vertical alinement with the post 4. A casting 6 is fixed upon the shaft 5 and upon the lower end of the post 4.

30 A bevel gear 7 is mounted upon the post 4 and rests upon the casting 6. A ratchet 8 is mounted upon the post 4 rigid with the bevel gear 7. A lever 9 has a bearing 10 loosely mounted upon the post 4 on top of the ratchet 8, so that the lever will swing freely in a substantially horizontal plane.

40 A weight 11 is attached to the outer end of the lever 9 and a pawl 12 extends from the lever 9 to engage the ratchet 8, so that when the weight swings one way the pawl will slip over the ratchet teeth and when the weight swings the other way the bevel gear 7 will be rotated.

45 A pinion 13 is fixed upon the pintle extending from the casting 6 and the pinion 13 meshes with the gear 7. A disk 14 is fixed to the pinion 13. Pins 15 and 16 are fixed through the disk 14. Conical rollers 17 and 18 are loosely mounted upon the 50 front ends of the pins 15 and 16.

A pivot shaft 19 is horizontally mounted behind the eye openings 20 and 21 and the eye-balls 22 and 23 are fixed upon this pivot shaft 19. A fan shaped arm 24 extends 55 backwardly from one of the eye-balls 22 and 23, said arm being flat horizontally.

Weights 25 and 26 are secured to the eye-balls 22 and 23 back of the pivot 19. Stops 27 and 28 are formed upon the eye-balls to limit the movement of the eye-balls relative to the sockets. 60

The parts are so arranged that the irises 29 are in their normal positions when the rollers 17 and 18 are out of contact with the arm 24, and the weights 25 and 26 have 65 restored the eye-balls to their normal positions with the stops 28 against the wall of the head.

At this time the doll is supposed to be upright and the doll is wide awake. If the head is tilted one way the weight 11 will swing freely upon the post 4, and if the head is tilted the other way as in putting the doll to bed, the weight 11 will swing the bevel gear 7 to operate the pinion 13, 70 to operate the rollers 17 and 18, to engage the arm 24 and elevate the arm until the stops 27 engage the wall of the head and the irises move step-by-step out of registration with the sockets and the doll goes to 75 sleep.

If the doll is laid flat on her back in a cradle and the cradle rocked, the weight or pendulum will swing back and forth, a ratchet tooth at a time, and gradually close 80 the eyes thereby producing the effect of rocking the doll to sleep.

Various changes may be made without departing from the spirit of my invention 85 as claimed.

I claim:

1. A combination with a hollow doll head having eye sockets, of eye-balls pivotally mounted and having irises to register with the sockets; stops to limit the up and down movement of the eye-balls on their pivots; an operating arm extending backwardly from the eye-balls; a pivoted lever mounted to swing in a horizontal plane; and means whereby the swinging of the lever 90 operates the eye-balls out of registration with the sockets.

2. A combination with a hollow doll head having eye sockets, of eye-balls fixed together and pivotally mounted, and having 95 irises to register with the sockets; an arm extending backwardly from the eye-balls; a weighted lever pivotally mounted to swing in a horizontal plane; a bevel gear; a pawl and ratchet connection between the lever 100 and the bevel gear; a bevel pinion meshing with the bevel gear; and means carried by 110

the bevel pinion for engaging the arm to raise the arm and move the irises out of registration with the sockets.

3. A combination with a hollow doll head having eye-ball sockets, of eye-balls fixed together and pivotally mounted and having irises adapted to register with the sockets; a weighted lever pivotally mounted in the hollow of the head; and means whereby the 10 swinging of the lever back and forth will operate the eye-balls to move the irises step-by-step out of registration with the sockets.

4. A combination with a hollow doll head having eye-ball sockets, of eye-balls fixed

together and pivotally mounted and having 15 irises adapted to register with the sockets; a weighted lever pivotally mounted in the hollow of the head; means whereby the swinging of the lever will operate the eye-balls to move the irises out of registration 20 with the sockets; and balancing weights for returning the eye-balls to their normal positions with the irises in registration with the sockets.

In testimony whereof I have signed my 25 name to this specification.

AUBREY D. McCROSKEY.
